Patented Dec. 28, 1926.

UNITED STATES PATENT OFFICE.

TERRELL F. SUMMERS, OF WILLOW, OKLAHOMA.

MAIL-BOX SUPPORT.

Application filed March 24, 1926. Serial No. 97,086.

This invention relates to supports and more particularly to a support by means of which a mail box may be conveniently mounted at one side of a road.

5 One object of the invention is to so construct the support that a mail box may be normally disposed in such position that the mail carrier may readily place mail therein.

Another object of the invention is to so 10 connect a box-carrying platform with a supporting post that the platform may be swung from a substantially horizontal position to a depending position out of the way of workmen who are repairing the road.

15 Another object of the invention is to provide the support with platform braces which may be readily moved into or out of operative engagement with the platform but are not liable to accidentally slip out of engagement with the platform.

Another object of the invention is to so 20 form the platform that an extension may be secured thereto and the mail box mounted upon the extension if so desired.

25 This invention is illustrated in the accompanying drawing, wherein—

Figure 1 is a perspective view showing the box-carrying platform supported in its 30 normal position and by dotted lines indicating the platform and box swung over the post;

Fig. 2 is a transverse sectional view through the box-carrying platform;

Fig. 3 is a fragmentary view in side elevation showing a portion of the platform and an extension secured thereto, and

Fig. 4 is a fragmentary longitudinal sectional view showing a modified construction.

The post 1 which is to be driven into the 40 ground near a road may be formed of wood or metal and preferably is provided with a tapered lower end so that it may be easily driven into the ground. If the post is formed of wood, it will, of course, be solid but if formed of metal it may be tubular. A rod is passed diametrically through the upper end of the post with its end portions projecting from opposite sides of the post to form arms 2, the extreme ends of which are threaded and carry securing nuts 3. A short bolt or pin 4 is passed diametrically through the post below the rod which forms the arms 2, and this bolt or pin 4 passes through eyes 5 formed at the inner ends of 45 the brace rods 6 so that the brace rods will be pivotally connected with the post inter-

mediate its height and at such distance from the ground that the rods may be swung downwardly to a depending position, as indicated by dotted lines in Fig. 1.

60 The platform 7 which is to carry a mail box 8 may be formed of wood or metal and is provided with openings to receive the bolts 9, by means of which the mail box is firmly secured to the platform. A recess 10 is

65 formed in the rear or inner end of the platform intermediate its width and is of such dimensions that the upper end portion of the post which projects above the arms 2 may pass through this recess when the platform is swung from the position shown in full lines to the position indicated by dotted lines. In order to mount the platform for 70 swinging movement from one position to the other, there has been provided hinges 11 which may be formed of sheet metal if so desired. These hinges are substantially U-

75 shaped and are adapted to straddle the arms 2 with their leaves 12 secured in overlapping relation to the platform by bolts or 80 other suitable fasteners 13. It will, of course, be understood that the rod from

85 which the side arms 2 are formed is to be passed through the post and hinges and the securing nuts 3 then engaged with the threaded ends of the rod. A cross bar 14 is secured to the under face of the platform

7 by bolts 14' and serves to brace the platform against warping. The cross bar is 90 preferably formed of metal and has its free ends reduced and threaded to provide stems

15 which are adapted to be engaged with the eyes 16 at the outer free ends of the brace rods 6. Nuts 17 are screwed upon the stems 15 so that the brace rods will be 95 firmly held in engagement with the stems.

It should be noted that the brace rods are formed of resilient metal so that, when they are swung upwardly to the operative position, they may be sprung into engagement 100 with the stems and by their own resiliency be held thereon if the securing nuts 17 should become detached from the stems and lost.

When this support is in use, the post is 105 driven into the ground adjacent the road and the mail box secured to the platform. The platform is then swung to a substantially horizontal position and the brace rods connected with the stems 15 to support the platform. The mail box will, therefore, be supported in such position that a mail carrier 110

driving along the road may readily place letters in the mail box. When a road is being repaired, the mail boxes often are in the way as they extend over the gutters at the sides of the road and, therefore, the workmen remove the post. By having the platform pivotally connected with the post, it is not necessary to remove the post from the ground as the brace rods 16 may be detached from the stems 15 and the platform either swung to the dotted line position or allowed to swing downwardly at the same side of the post from which it ordinarily extends. If it is found that, when the post is embedded in the ground, the platform 7 is not of sufficient length to permit the mail box to be readily reached by a carrier driving along the road, an extension 18 may be secured to the platform by the bolts 19 and the mail box secured to the extension.

In Fig. 4 there has been shown a modified construction. Referring to this figure it will be seen that instead of having the cross bar 14 rigidly secured to the platform by bolts 14' which pass through openings frilled in the platform, the platform has been formed with a longitudinally extending slot 20 in which a bar securing bolt 21 is received. This bolt is slidable in the slot and as its head is countersunk it will not have binding engagement with the bottom of the mail box. Therefore, the platform can be swung from the normal position shown in full lines in Fig. 1 to the position indicated by dotted lines without detaching the rods 6 from the ends of the cross bar. It will be obvious that more than one slot 20 and screw 21 may be provided if desired.

Having thus described the invention, I claim.

1. A device of the character described comprising a post, a platform pivotally connected with said post and adapted to be swung over the upper end thereof from one side of the post to the other, and braces attached to said post below said platform and detachably connected with said platform at opposite sides thereof to support the platform in substantially a horizontal position.

2. A device of the character described

comprising a post, a platform pivotally connected with said post and adapted to be swung over the upper end thereof from one side of the post to the other, a bar extending transversely of said platform and secured thereto with its ends projecting from the sides of the platform, and braces pivoted to said post and at their outer ends provided with eyes adapted to engage the ends of said bar and support the platform in substantially a horizontal position.

3. A device of the character described comprising a post, a platform pivotally connected with said post and adapted to be swung over the upper end thereof from one side of the post to the other, a bar extending transversely of said platform and secured thereto with its ends projecting from the sides of the platform, the projected ends of said bar being reduced and threaded, a pin passed through said post below said platform, brace rods for said platform pivoted upon said pin and at their outer ends formed with eyes to engage the reduced ends of said bar, and nuts screwed upon the reduced ends of said bar to retain the eyes of said rods in engagement therewith.

4. A device of the character described comprising a post, a platform pivotally connected with said post and adapted to be swung over the post from one side thereof to the other, a cross bar extending transversely beneath said platform and slidable longitudinally thereof, and brace rods pivotally connected with the ends of said cross bar and opposite sides of said post.

5. A device of the character described comprising a post, a platform pivotally connected with said post and adapted to be swung over the post from one side thereof to the other, a cross bar extending transversely beneath said platform, said platform being provided with a longitudinally extending slot, a fastener carried by said cross bar and slidable longitudinally in said slot, and brace rods pivotally mounted upon the ends of said cross bar and pivotally connected with said post at opposite sides thereof intermediate its height.

In testimony whereof I affix my signature.
TERRELL F. SUMMERS. [L. s.]
